SAMUEL H. MCKNIGHT, OF JERSEY CITY, NEW JERSEY, ASSIGNOR TO TROY LAUNDRY MACHINERY COMPANY, INC., OF NEW YORK, N. Y., A CORPORATION OF DELAWARE

RESILIENT PADDING

Application filed December 21, 1927. Serial No. 241,559.

This invention relates to resilient paddings, especially to paddings suitable for pressing or ironing machines either of the cylindrical or platen type.

5 The invention has for its object to provide a resilient padding which is economical of manufacture, and is particularly well suited to pressing machines having presser members subjected to relative transverse or lateral movements. In machines of this latter type such, for example, as flat work ironers employing spring paddings, unless the springs are properly anchored either to a base plate or to the pad covering, the springs tend 10 to become distorted and eventually break after prolonged use. In paddings heretofore devised and employing a plurality of individual spring members for supporting the pad fabric, various expedients have been devised for anchoring the ends of the springs to the pad base as well as to the pad covering. However, it has been found that, particularly in flat work ironers, when unusual thicknesses of material such as buttons or the 15 like pass through the ironer that the pressure on individual springs is greatly increased and in some cases causes breakage thereof. Accordingly, it is a further object of the present invention to provide a plural spring padding 20 for pressing machines wherein the individual springs are so interconnected that during compression or angular displacement the load or pressure is divided between one spring and a plurality of adjacent springs.

25 A feature of the invention resides in a plural spring pad having means for coupling together a plurality of individual springs whereby the springs may be individually compressed and whereby undue lateral movement of the springs is prevented.

Another feature of the invention pertains to a unitary spring padding having a plurality of individual springs securely fastened to a base plate and connected at their 40 upper ends by means of loose coupling links.

A further feature pertains to the manner of attaching the springs of a resilient pad to the pad base plate.

A still further feature is concerned with a 45 spring pad employing spaced resilient spring

members which also serve as a support for the pad fabric, together with means for providing support to the fabric at the places where the springs are separated.

Other features and advantages will be apparent after a consideration of the following description and the appended claims.

While the invention is disclosed in the drawing as applied to a cylindrical or flat-work ironing machine, it is understood that 55 it is equally applicable to platen type presses. Accordingly, Fig. 1 of the drawing shows a portion of an ironing roll having attached thereto a resilient spring pad according to the invention.

Fig. 2 shows a plan view of the portion of the spring padding shown in Fig. 1.

Fig. 3 is a schematic showing of the manner in which the base plate is prepared for the securing of the springs thereto.

Fig. 4 is an alternative arrangement to that disclosed in Fig. 3.

Fig. 5 shows another type of spring which may be employed in place of the cylindrical springs shown in Figs. 1 and 2.

Fig. 6 shows a detail of the spring coupling links prior to the closing of the ends thereof.

Referring more particularly to Fig. 1, there is represented by the numeral 1 a portion of the cylindrical roll of a flat work ironer to which the spring pad unit is adapted to be secured in any suitable manner such, for example, as by providing the metal base of the pad with overlapping edges which 80 hook together, or by fastening the metal base to the roll by means of bolts, rivets or the like. The former method of fastening is preferable as it enables the pad to be removed easily when repair or replacement is 85 necessary. The pad unit comprises a base plate 2 which is preferably of non-corrosive metal in sheet form and is of a length sufficient to cover the working surface of the ironing roll. Mounted on the base plate at

90 suitably spaced points there are a plurality of springs 4 of brass or the like and preferably cylindrical in shape. Springs 4 may be provided with any desired number of turns to give the requisite resiliency to the 95 100

pad and to separate the pad covering from the base plate 2 the required distance. The upper end of the springs 4 serve as a support for the covering 5 which may comprise layers of felt, canvas, etc., as is well known in the art. For the purpose of securing the lower ends of springs 4 to the base plate 2 the said plate has portions 3 punched out therefrom, as shown clearly in Fig. 3, the remaining portions provide a plurality of tongues which are employed for the purpose of anchoring the lower ends of the springs. For this purpose the tongues 4 are first bent upwardly to the position shown in the left-hand end of Fig. 1. The springs 4 are then assembled on the base plate with the lowermost turns 7 embracing the tongues 6 which are thereupon turned back upon themselves to form eyelets serving to securely hold the spring to the base plate. While four of these struck-up portions or tongues are provided for the bottom turn of each spring it will be understood that any other number may be provided. However, it has been found that four tongues struck-up at diametrically opposite points, as shown in Fig. 3 securely anchor the springs to the base plate and prevent relative movement therebetween.

As shown in Fig. 1, the uppermost turn 30 of each spring is kinked at diametrically opposite points to provide depressions 9 adapted to receive the links 10. Links 10 are preferably made from brass or other non-corro- 35 sible metal and of sufficient diameter to prevent buckling under the maximum working pressure. As shown in Fig. 6 links 10 are prepared from a straight metal strip, with the ends bent back upon themselves to provide hook-like portions 14. These hooked 40 portions are then engaged with the kinks 9 in the upper turns of adjacent springs and further closed to provide the eyelets 11. By this arrangement the springs are permanently spaced and are prevented from interfering 45 with one another either during compression or when subjected to lateral forces.

As shown in Fig. 2, four links are provided for each spring. However, it will be understood that any other desired number 50 may be employed. It is obvious from the arrangement disclosed that when a single spring is subjected to a compressing force the entire load is not borne solely by said spring but is partially transferred through 55 the links 10 to adjacent springs. If desired, the eyelets 11 may be sufficiently small as to provide a rigid connection between adjacent springs. It may be desirable, however, to have the eyelets 11 loosely embrace the 60 springs so that each spring when subjected to a load will be compressed a certain distance before the pressure is transferred to the adjacent springs. Links 10 in addition to functioning as members for equalizing the 65 load on the spring padding also serve as

spacer members between the springs. This latter feature is particularly advantageous in roller type machines since generally the roller is required to move past a fixed cooperation head and consequently the springs 70 4 have a tendency to crowd upon each other in a direction opposite to that in which the roll is rotating. Not only is interference between adjacent springs probable in such cases but also when thick garments are passing 75 through the machine the force is in some cases of sufficient magnitude to entirely remove the spring from the base plate. It is clear therefore that with a padding of the type disclosed, as the roll rotates and the 80 springs tend to move from a vertical position out of radial alignment there is an opposing force transmitted from the springs not subjected to pressure through the links 10, tending to hold the strained springs in 85 their normal straight position. By this arrangement therefore the pad has in effect both a vertical resiliency as well as a lateral resiliency.

It will be obvious that after the press plate 1 has been punched, as above described, and the tongues 6 are turned back upon the lower ends of the springs there is remaining a perforation in the base plate. This perforation 90 acts as a communication between the interior of the roll 1 and the space between the base plate 2 and the covering 5 and may be used to convey steam to the interior of the padding or for the purpose of enabling a vacuum 95 created therein, for which purpose a suitable suction creating means is connected to the interior of drum 1.

Fig. 4 shows an alternative method of preparing the base plate 2 for the purpose of providing perforations and anchoring means for the springs. In this modification the plate is provided with perforations 12 preferably at the points where the individual springs are to be mounted. The remaining portion of the plate between each perforation is provided with a struck-up tongue 13 which is adapted to be folded over toward the center of the perforation 12 to form an eyelet. This manner of preparing the plate, however, requires separate perforating and punching operations.

If desired, instead of employing cylindrical helical springs, springs having an hour glass shape, as shown in Fig. 5, may be provided. Springs of this latter type are capable of being distorted from their vertical position to a greater extent without injury to the spring than is capable with cylindrical springs. This feature it is obvious may in certain cases be found to be advantageous in roller type presses. Furthermore, employing this type of spring the padding may be compressed to a greater extent without causing interference or binding of the individual 120 spring turns with one another.

The resilient paddings described above provide a stable, economical and easily assembled unit and one which does not require the pad fabric to be permanently attached to the upper ends of the springs. It is well known that with paddings of this latter type, namely those having the fabric secured to the springs, that after continued use the springs tend to tear the fabric material and in order to replace the fabric with a new one it is necessary to remove the entire padding in order to disconnect the individual springs from the fabric.

In accordance with the present invention the upper ends of the springs being permanently spaced by the members 10, the fabric 5 may be simply wrapped around the exterior thereof and suitably fastened at the ends. When replacement of the fabric is required it is not necessary to remove the pad proper from the roll 1.

What I claim is:

1. In an ironing machine, the combination of a perforated ironing roll, a metal plate 25 adapted to be wrapped around said roll and having overlapping edges for securing said plate in position on said roll, a plurality of tabs struck up from said plate to provide perforations registering with the roll perforations, a plurality of springs fastened to said plate by said tabs and in registry with said perforations, and strain distributing links 30 loosely interconnecting the upper end of said spring and the upper ends of adjacent springs.

2. In combination a perforated ironing roll, a plate having portions struck out therefrom to provide perforations and a plurality of tongues, said plate being mounted on said roll with the plate perforations registering with the roll perforations, a plurality of springs 40 mounted on said plate and adapted to be fastened thereto through the intermediary of said tongues, a pressing fabric supported by the upper ends of said springs, the upper ends of all adjacent springs being loosely inter-linked.

3. A resilient pad for a laundry machine comprising a base plate of non-corrosive metal, said plate having a plurality of struck-up 50 portions to provide tongues and perforations, a plurality of springs each mounted on said plate at the struck-up portions thereof and adapted to be secured thereto through the intermediary of said tongues, the upper ends of said springs being loosely linked together 55 whereby said springs may be individually compressed and the angular displacement of the upper end of any individual spring will be transmitted to all the adjacent springs.

60 In testimony whereof, I have signed my name to this specification, this 14th day of December, 1927.

SAMUEL H. McKNIGHT.
